CLAIM

The ornamental design for a string trimmer accessory, as shown and described.

DESCRIPTION

FIG. 1 is a perspective view of a string trimmer accessory, showing my new design;

FIG. 2 is another perspective view thereof;

FIG. 3 is a front elevation view thereof, the rear elevation view is identical;

FIG. 4 is a left side elevation view thereof, the right side elevation view is identical;

FIG. 5 is a top plan view thereof;

FIG. 6 is a bottom plan view thereof;

FIG. 7 is a partial enlarged view of FIG. 1;

FIG. 8 is a partial enlarged view of FIG. 1;

FIG. 9 is a partial enlarged view of FIG. 1;

FIG. 10 is a partial enlarged view of FIG. 2; and,

FIG. 11 is a partial enlarged view of FIG. 2.

The dash-dash broken lines shown in the drawings are included for the purpose of illustrating portions of the string trimmer accessory that form no part of the claimed design. The long dash-long dash broken lines of FIGS. 1 and 2 depict the limits of the enlarged views and form no part of the claimed design. The dot-dash lead lines in FIGS. 1 and 2 labelled 7, 8, 9, 10, and 11 indicate the areas from which the enlargements in FIGS. 7-11 are taken and form no part of the claimed design.
